(57) **CLAIM**

The ornamental design for a catheter securing device, as shown and described.

DESCRIPTION

FIG. 1 is a front, left, and top perspective view of a catheter securing device.

FIG. 2 is a back, right, and bottom perspective view of the catheter securing device of FIG. 1.

FIG. 3 is a front elevational view of the catheter securing device of FIG. 1.

FIG. 4 is a back elevational view of the catheter securing device of FIG. 1.

FIG. 5 is a top plan view of the catheter securing device of FIG. 1.

FIG. 6 is a bottom plan view of the catheter securing device of FIG. 1.

FIG. 7 is a right elevational view of the catheter securing system device of FIG. 1; and,

FIG. 8 is a left elevational view of the catheter securing device of FIG. 1.

The broken line portions show unclaimed subject matter only and form no part of the claimed design.

1 Claim, 4 Drawing Sheets

Related U.S. Application Data

division of application No. 29/695,838, filed on Jun. 21, 2019, now Pat. No. Des. 907,768.
